WATER SUPPLY SYSTEM FOR PASSENGER CARS

Herbert J. Matje, West Allis, Wisc.

Application September 8, 1943, Serial No. 501,558

3 Claims. (Cl. 222—394)

In a water supply system for passenger cars heretofore in vogue, water is delivered to a tank from one side of the car through a special five-way valve, which controls the water and the compressed air by which the water is forced from the tank to the basins, bowls, or other places of use in the car. (See Car Builders' Cyclopedia, 1937, p. 761.) With this system, the necessity of filling from one side of the car only is objectionable in service, and the five-way valve is costly to buy and to maintain.

The principal object of this invention is to overcome these and other objections and to provide a system that can be filled from each side of the car and that includes only valves, fittings, etc., that are standard everywhere and that can be advantageously secured for original installation and readily maintained and replaced throughout the country.

In the drawing:

Fig. 1 is a diagram representing the water supply system on a passenger car without particular regard to actual location on the car;

Fig. 2 is a cross section through two three-way valve cocks, one at each side of the car in the system, and in the position they assume when water is being delivered to the car;

Fig. 3 is a similar section through those valve cocks in the position they assume when the system is being filled with water from the right of the car; and

Fig. 4 is a similar section through those valves showing the positions they assume when the system is being filled with water from the left side of the car.

But this drawing and the corresponding description are used for the purpose of disclosure only, and are not intended to place unnecessary limitations on the claims.

Water for the system is stored in a tank 10, which may be filled through a nozzle 11 at the right, or a nozzle 12 at the left, connected with a forked filling line 13 leading into the tank through a main line 14. Each fork of the filling line 13 is provided with a familiar form of check valve 15.

Water is delivered from tank 10 through a feed line 16 equipped with a control valve cock 17 and leading to the piping system on the car indicated in the diagram Fig. 1 by the arrow 18.

Water is forced from the tank 10 through the car by compressed air, preferably, as shown in this instance, by air from the car brake supply reservoir 19 through an air supply line 20 equipped with a check valve 21, a governor valve

22, a reducing valve 23, a second check valve 24, a three-way spring loaded valve cock 25 at the left of the car, and a similar three-way, spring loaded valve cock 26 at the right of the car, and finally leading into the tank 10 at 27 near the top.

The governor valve 22 and the reducing valve 23 are standard for all railroads in this country, and are substantially the same as shown in the Car Builders' Cyclopedia, 1937, at page 761.

Air entering from the left in Fig. 1, after a suitable pressure has been obtained—for instance, 60 pounds—passes through the non-return governor valve, and is then reduced to a pressure suitable for the storage system (20 pounds) by passing through the reducing valve 23. Thus, the water in the system is maintained under the selected pressure, such as 20 pounds, throughout the draft on a charge or filling. In use for delivery of water to the car, the cocks 25 and 26 are in the position shown in Fig. 2, and the check valves 15 automatically close and remain closed due to the pressure in the system.

When the system is to be filled, as it should be at suitably selected points along the run, the selected valve cock 25 or 26 is set to the proper position, and the filling hose is applied to the nozzle 11 or 12. If the filling is to be done from the right of the car, the valve cock 26 is set as shown at the right in Fig. 3 while the valve cock 25 remains in normal closed position. Then the hose is applied to the nozzle 11, and the pressure of the water lifts the check valve 15, and the water passes through the filling line 13 and the main line 14 into the tank 10. When the water level in the tank rises to or above the connection 27, water flows outwardly in the overflow line 34 and reaches the valve cock 26, which, as indicated at the right in Fig. 3, is then open at 30 to exhaust the air. As soon as water flows from that cock, the operator knows the system is filled. He removes the hose from the nozzle 11, and turns the valve cock 26 back to the position shown at the right in Fig. 2, thus sealing the system.

If the filling is to be done from the left of the car, the valve 25 is turned to the position shown at the left in Fig. 4, while the valve 26 remains in the position shown at the right in that figure.

The hose is then applied to the nozzle 12. The water passes through the filling line, lifting the check valve 15, and entering the tank through the main line 14. Again, when the water in the tank rises above the connection 27, it flows out through the overflow line 34, past the valve cock

26, around to the valve cock 25, which, as seen from the left of Fig. 4, is open to exhaust at 31. Then, when water escapes from that exhaust, the operator knows that the system is filled; he returns the valve 25 to the position shown in Fig. 2, 5 and removes the hose from the nozzle 12.

It will be noted that, in turning the valve 26 to the position shown at the right in Fig. 3, or the valve 25 to the position shown at the left in Fig. 4, the air in the system is exhausted to the atmosphere, so that the water is entered against only a little more than atmospheric pressure.

The governor valve and the reducing valve being standard on all railroads in the country and the nozzles 11 being capable of choice from several that are standard on all railroads in the country, they may be readily secured at low cost in appropriate supply and maintained in the storehouses throughout any railroad system. The other valves and fittings, pipes, etc., in the system are standard for plumbing and steam fitting and are available everywhere in the country. On account of this selection of parts, the system is easily installed and maintained.

The provision for filling from each side saves much time and contributes a great deal to the safety in operation, for, when the car must always be filled from one side, it frequently becomes necessary for the attendant to pass under a car with the hose, involving the well known danger.

For convenience in locating trouble, the air supply line is equipped with cocks 32 and 33 of any suitable construction.

I claim:

1. In a water supply system for a railway passenger car, a water tank, a filling inlet in each side of the car connected with the tank, a compressed air supply pipe connected to a source of air pressure and with an upper level of the tank, and two three-way valve cocks in the air supply 40 pipe, one at each side of the car and each having

two normally connected ports, one open to the source of air pressure and one open to the water tank, and having one normally closed exhaust port, whereby the water tank may be filled from either side of the car by positioning the valve cock on said side to close the air pressure port and open the tank port to the exhaust port and then filling through the inlet on said side until water escapes from said exhaust port.

2. In a water supply system for a railway passenger car, a water tank, a filling inlet at each side of the car connected with the tank, a compressed air supply pipe connected with an upper level of the tank for normally applying pressure to the water, and means for removing said pressure during filling comprising a valve operable from each side of the car adapted to close the connection between the air supply pipe and the tank and open a connection between the tank and atmosphere, so that first the air in the tank and then some of the water will be discharged to atmosphere as the filling operation proceeds.

3. In a water supply system for a railway passenger car, a water tank, a filling inlet at each side of the car connected with the tank, a pipe communicating with an upper level of the tank for normally connecting the pressure of an air supply to the water, and means for removing said pressure during filling comprising a three-way 30 valve in said pipe at each side of the car, each valve having ports for normally connecting the two valves, the tank and the air supply in series, and each having an exhaust port by which the valve may be set to disconnect the air supply and the tank and open the tank to the exhaust port, whereby the tank may be filled from either side of the car and first air and then water will be discharged from the exhaust port of the valve on said side.

HERBERT J. MATJE.
